UNITED STATES PATENT OFFICE.

SIDNEY LÉ FÈVRE VARVEL, OF MELBOURNE, VICTORIA, AUSTRALIA.

ELECTRICAL WATER-HEATER.

1,139,001.

Specification of Letters Patent. Patented May 11, 1915.

Application filed November 18, 1914. Serial No. 872,686.

To all whom it may concern:

Be it known that I, SIDNEY LÉ FÈVRE VARVEL, a subject of the King of Great Britain, residing at 380 William street, Melbourne, in the State of Victoria, Australia, have invented certain new and useful Improvements in Electrical Water-Heaters; and I do declare the following to be a full, clear, and exact description of the invention, such as will enable others skilled in the art to which it appertains to make and use the same.

This invention relates to an improved electric water heater, such heater being constructed to give a high efficiency with a minimum amount of electricity. The heater is simple in construction and can be manufactured and sold at a small cost.

In order that my invention may be the more easily understood, reference may be made to the accompanying drawings, in which—

Figure 1 is a sectional elevation of apparatus embodying my invention, while Fig. 2 illustrates a sectional elevation of a modification showing another apparatus also embodying my invention.

In the accompanying drawings *a* is an annular limb or cylinder, hereinafter termed the inner annular limb or cylinder, of suitable metal forming a good conductor of heat, such as copper. The inner wall *b* of this annular limb is surrounded with a mica sheet or tube *c* or any such material, which may offer good electrical resistance. Around this wall *b*, which will now be insulated, is wound, in the form of a helix, nichrome wire, German silver, or any other wire *d* that may offer a high specific resistance. Each end of this helix resistance is preferably fastened by clamps *e* around the wall *b* of the annular limb or cylinder *a* to secure the fastening of the helix; conductors taken from these points lead through suitable insulated metal tubes *f* and *g* connected to the top flange *h* and insulated ring *h'* and pass through the top (not shown on the drawings) of the outer annular limb or cylinder hereinafter described for connection to the terminals. The space *i* between the two walls of the inner annular limb or cylinder

a is now filled with oil or other liquid that may prevent the oxidization of the wire *d* and at the same time act as a transferring medium for the heat generated. Alternatively this space may be filled up with metal of low specific heat, or any other suitable solid for the conduction of heat. A vent hole *j* may be provided at the top of the element to allow the escape of any pressure in the event of the oil or the like becoming overheated.

The annular limb or cylinder is inclosed within another annular limb or cylinder as *m* of corresponding shape and of such a size as will allow spacing members *k* to be placed between the two outer walls and between the two inner walls, so that when the inner annular element *a* is placed within the outer shell *m'* of the annular limb *m* two cylindrical spacings *n* are created between the element and said outer shell.

At the bottom of the outer shell of the annular limb *m* is fixed an inlet pipe *o* for the supply of the water and at a suitable point at the top of the same shell is fixed an outlet tap *p* for drawing off the heated water.

In the construction illustrated in Fig. 2 the fiber or porcelain flanges *h* and ring *h'* are divided and are of such configuration as to enable them to be easily inserted between the walls of the inner annular limb *a* containing oil or the like. The said rings *h'* are separated from each other by means of rods *r*, suitably attached, such rods being of either electric conduction or insulating material.

Around each rod *r* is wound the heating element consisting of a number of turns of the nichrome wire *d* or ribbon, preferably as before explained, in helix form. Should the rods *r* be constructed of conducting material, an insulating medium such as glass, silica or the like *s* may be interposed between the heating element and the rod *r* in such a position as to insure good electrical insulation between them. The ends of these elements are suitably attached to the fiber rings *h'* by fasteners *u* to allow an effective and simple connection to be made between any of the elements and at the same time

to keep the element taut and prevent the turns from touching.

Any number of such rods r may be employed and connected either in series or in parallel. The unit so constructed is, as before stated, placed between the walls of the inner annular limb a containing the oil, lead, sand or other suitable substance in a position to prevent any of the electric conducting portion of the unit making contact with the inner surface of the annular limb, and if necessary, an insulating medium of porcelain or mica may be interposed for this purpose.

15 Suitable leads may be attached where necessary to the heating unit. The inner annular limb a may be held in position by supports t placed within the outer shell m' of the limb m at desired intervals apart.

20 The action of my apparatus is as follows:—The electricity is passed through the helix resistance and heat is instantly generated and delivered to the walls of the heating element through the medium of the oil 25 or other suitable substance as previously mentioned. The water which has been led into the bottom of the shell rises up the two narrow cylindrical spaces, at the same time absorbing the heat generated by the element. As the water reaches its required 30 temperature it is drawn off at the top by means of a tap.

The device may be suitably fitted if desired with a combination tap, so that when 35 the water is turned on the current flows through the element and vice versa. The apparatus may also be fitted with terminals suitably constructed to prevent any leakage of oil and at the same time to be connected 40 up to any electrical supply.

I claim:—

1. An electrical fluid heater comprising two cylindrical walls forming an annular space, a closed annular member formed by 45 two further cylindrical walls, with end closing members, located in said annular space, a helically wound high resistance wire located within said closed annular member, a heat conducting medium filling said closed 50 annular member, means for introducing cold liquid into the lower end of said annular space below said closed annular member, and means for drawing off hot liquid from the top end of said annular space above said closed annular member, said liquid being permitted to flow upwardly on both sides of the closed annular member simultaneously.

2. An electrical fluid heater comprising two cylindrical walls forming an annular space, a closed annular member formed by 60 two further cylindrical walls, with end closing members, located in said annular space, a helically wound high resistance wire located within said closed annular member, a heat 65 conducting medium filling said closed annular member, means for introducing cold liquid into the lower end of said annular

located within said closed annular member, insulated tubes on the said closed annular 65 member for connecting the resistance wire to external terminals, a heat conducting medium filling said closed annular member, means for introducing cold liquid into the lower end of said annular space below 70 said closed annular member, and means for drawing off hot liquid from the top end of said annular space above said closed annular member, said liquid being permitted to flow upwardly on both sides of the closed 75 annular member simultaneously.

3. An electrical fluid heater comprising two cylindrical walls forming an annular space, a closed annular member formed by 80 two further cylindrical walls, with end closing members, located in said annular space, a helically wound high resistance wire located within said closed annular member, a liquid heat conducting medium filling said closed annular member, a vent pipe leading 85 from the top of said closed annular member, means for introducing cold liquid into the lower end of said annular space below said closed annular member, and means for drawing off hot liquid from the top end of 90 said annular space above said closed annular member, said liquid being permitted to flow upwardly on both sides of the closed annular member simultaneously.

4. An electrical fluid heater comprising 95 two cylindrical walls forming an annular space, a closed annular member formed by two further cylindrical walls, with end closing members, located in said annular space, a high resistance wire helically wound 100 around the inner wall of the closed annular member and within said closed annular member, a heat conducting medium filling said closed annular member, means for introducing cold liquid into the lower end of 105 said annular space below said closed annular member, and means for drawing off hot liquid from the top end of said annular space above said closed annular member, said liquid being permitted to flow upwardly 110 on both sides of the closed annular member simultaneously.

5. An electrical fluid heater comprising two cylindrical walls forming an annular space, a closed annular member formed by 115 two further cylindrical walls, with end closing members, located in said annular space, longitudinal spacing members located on both sides of the closed annular member between the cylindrical walls of the same and the other aforesaid cylindrical walls, a helically wound high resistance wire located within said closed annular member, a heat 120 conducting medium filling said closed annular member, means for introducing cold liquid into the lower end of said annular

space below said closed annular member, and means for drawing off hot liquid from the top end of said annular space above said closed annular member, said liquid being permitted to flow upwardly on both sides of the closed member simultaneously.

In testimony whereof I have signed my

name to this specification in the presence of two subscribing witnesses.

SIDNEY LÉ FÈVRE VARVEL.
